UNITED STATES PATENT OFFICE.

GEORGE S. STRONG, OF NEW YORK, N. Y., ASSIGNOR TO JOHN P. MURPHY,
OF PHILADELPHIA, PENNSYLVANIA.

ENGINE-STARTING DEVICE.

SPECIFICATION forming part of Letters Patent No. 650,434, dated May 29, 1900.

Application filed September 1, 1899. Serial No. 729,178. (No model.)

To all whom it may concern:

Be it known that I, GEORGE S. STRONG, a citizen of the United States of America, residing in the city, county, and State of New York, have invented a certain new and useful Improvement in Engine-Starting Devices, of which the following is a true and exact description, reference being had to the accompanying drawings, which form a part thereof.

10 My invention relates to a device for rotating the driving-shaft of an engine independently of the parts of the engine normally acting on the shaft, so as to start the engine in operation. Particularly my invention is adapted for use in connection with gas-engines.

My invention embodies certain features of and is in effect an improvement upon my former invention described and claimed in 20 my application for a patent, Serial No. 715,696, filed May 5, 1899, my object in the present case being to provide an improved starting mechanism more positive and reliable than that described in my former patent, and particularly one which is adapted to be driven by power.

Reference being now had to the drawings in which my invention is illustrated, Figure 1 is a plan view of a portion of a gas-engine, 30 showing a general position in which I have found it convenient to apply my device. Fig. 2 is a longitudinal horizontal section through the end of the shaft and my starting mechanism connected therewith. Fig. 3 is a cross-sectional view taken on the line 3 3 of Fig. 2, and Fig. 4 is a longitudinal section taken as on the line 4 4 of Fig. 3.

A indicates the casing of the engine proper. (Not shown in detail.)

40 A' indicates a bearing formed in the casting; a', a steel liner in the bearing.

B is a bracket bolted to the casing A and having formed through its end a cylinder B', which surrounds the shaft and supports a cylindrical clutch-ring (indicated at b') beyond the cylindrical passage B'. A cylindrical chamber B² is formed in the bracket B and surrounded by a flange B³, as indicated.

C indicates the driving-shaft of the engine, 50 which is shown as centrally perforated to give passage to the fluid for the purposes described

in my application for a patent, Serial No. 698,623, filed December 8, 1898. The perforation is indicated at C', enlarged, as indicated at C², toward the outer end of the shaft, 55 again enlarged, as indicated at C³, and internally threaded, as indicated at C⁴, the outer projecting end of the shaft being also externally threaded, as indicated at C⁵. Fitting in the enlarged cylindrical passage C² is the 60 perforated cylinder D, having a cylindrical enlargement, as indicated at D', which fits into the cavity C³, and an outer extending part D², which projects beyond the end of the shaft and is externally threaded, as indicated 65 at D³.

E is an externally-threaded cylinder which fits over the end D² of the cylinder and screws into the threaded cavity C⁴ of the shaft, E' indicating its head.

70 F is a nut screwing on the threaded end C⁵ of the shaft and serving to hold in place the cylindrical plate J'.

G indicates roller-bearings supporting the shaft and working between the hard-steel 75 liner a' and the similar liner c, attached to the shaft.

H is a cylinder fitting over and keyed to the shaft C and having its outer end flanged, as indicated at H', and resting against the angular plate J.

I indicates governing mechanism supported on the ring H, but which, forming no part of my present invention, need not be described.

K is a bracket-casting secured to the flange 85 B³ of the bracket B and having formed in it the cylindrical chamber K', which supplements and forms an inclosed cylindrical chamber with the portion B² of the bracket B. There is also formed in the bracket K the 90 passage indicated at K² K³, opening inward through the threaded passage K⁴, into which screws the threaded nut D³ of the cylindrical tube D² D, L indicating a jam-nut for holding it in place.

95 K⁵ indicates a threaded opening through the head of the bracket K, which is closed by the screw-plug K⁶.

M is a clutch-ring secured to the shaft C and having formed in it a series of angular recesses M', inclined in one direction only, as clearly shown in Fig. 3. This clutch-ring ex-

tends through the cylinder B' and also through the cylindrical chamber B² K', as shown in Fig. 2.

O and O, &c., and O' O', &c., are rollers, 5 two resting in each of the inclined cavities M' of the clutch-ring M, as shown in Fig. 2, one set lying beneath the clutch-ring b' and the other set lying beneath the clutch N', to which is secured the worm-wheel N, working in the 10 chamber B² K'.

P is a casing for the worm, preferably made in two parts, as shown, one part P' being attached to the bracket B and the other part P² attached to the bracket K.

15 Q is the worm-shaft, preferably working in roller-bearings, as indicated at Q², and having secured to it the worm Q', in engagement with the worm-wheel N.

When it is desired to start the engine, the 20 shaft Q is rotated, turning the worm Q' and through it the worm-wheel N and clutch-ring N', secured to it, which is journaled on the recessed clutch-ring M and which when turned in one direction causes the rollers O' to move 25 up on the inclines M' and tightly clutch the members M and N' together, so that the shaft C will rotate with the clutch. This rotation of the engine-shaft is continued until the engine goes into operation, turning the shaft 30 with greater rapidity than it is being turned by means of the worm, the consequence of which is that the clutch-ring N' moves backward with respect to the clutch-ring M, causing the rollers to move backward toward the 35 bottom of the inclines and permitting the clutch-rings to move independently of each other.

A particular merit of my device is that it 40 enables the engine to be started with an even steady movement of the shaft and at the same time provides in addition an automatic clutch which prevents at all times a backward movement of the shaft, because when the worm-wheel N is stationary it is locked in position by 45 the worm, and if the shaft moves backward

it is at once clutched to the member N' and held stationary, because a backward movement of the shaft has obviously the same tendency to engage the two members of the clutch together as a forward movement of the clutch-ring M'. As an additional precaution against the backward movement of the shaft, I still employ the permanent clutch formed between the member M and the clutch-ring b', which serves the same function as described with 55 reference to this construction in my former patent.

Having now described my invention, what I claim as new, and desire to secure by Letters Patent, is—

1. In combination with the shaft of an engine a clutch arranged to engage with the shaft when moved in one direction and to disengage when the movement is in the other direction, a worm-wheel secured to a clutch member and a worm in engagement with said wheel for driving it and through the clutch the shaft of the engine.

2. In combination with the shaft of an engine, a clutch arranged to engage with the shaft when moved in one direction and to disengage when the movement is in the other direction, a worm-wheel secured to a clutch member, a worm in engagement with said wheel for driving it and through the clutch 75 the shaft of the engine and a casing inclosing the worm-wheel and worm.

3. In combination with the shaft of an engine, a clutch-ring, as M, surrounding and secured to said shaft and having inclines M' sloping in one direction, a clutch-ring, as N', fitting and turning on ring M, rollers O' situated in the inclines M', a worm-wheel N secured to ring N', a worm Q' in engagement with said worm-wheel and means, as shaft Q, 80 for actuating the worm.

GEORGE S. STRONG.
